PROCESS OF MAKING SHOE FORMS

Original Filed April 8, 1926

UNITED STATES PATENT OFFICE

WILLIAM J. DE WITT, OF AUBURN, NEW YORK, ASSIGNOR TO THE SHOE FORM CO., INC., OF AUBURN, NEW YORK, A CORPORATION OF NEW YORK

PROCESS OF MAKING SHOE FORMS

Original application filed April 8, 1926, Serial No. 100,667. Divided and this application filed May 27, 1927. Serial No. 194,660.

This invention pertains to a process of making hollow forms or fillers of that type intended for insertion in a finished shoe to preserve its lasted shape while on exhibition or during transportation or storage and the principal object of the present invention is to provide a novel method of forming a hollow form of light weight and of resilient material having improved structural characteristics and functional utility. The present application is a division of my copending application, Serial No. 100,667, filed April 8, 1926.

Since forms of this general type are used to a large extent by travelling salesmen for preserving the shape of sample shoes and since the persons to whom such sample shoes are exhibited are highly discriminating and critical and insist upon inspection of the interior as well as the exterior of the shoe, it is necessary, when usual forms are employed, to withdraw the form during inspection of the shoe. The withdrawal of the form permits the shoe upper to collapse, to some extent at least, so that, at the very moment when it is most desirable to have the shoe appear at its best, its internal support is withdrawn and its desirable characteristics may thus to a certain extent disappear. Moreover the repeated withdrawal and reinsertion of the form tends to stretch the shoe, particularly when the shoe is made of the thinner and finer materials. In accordance with the present invention this difficulty is avoided since the interior of the shoe is fully exposed to view while the form is in position therein.

Most shoe forms, if hollow, are provided with an inturned bottom flange and when such forms are made of sheet material, moulded to shape, the toe portions of the flange contain plaits or wrinkles which detract from its appearance, increase the effective height of the form at the toe, and to some extent interfere with its insertion in or withdrawal from the shoe. In accordance with the present invention this difficulty is eliminated and the flange is smooth and devoid of plaits at the toe.

One of the most popular styles of shoe for women's wear is the strap pump. Hollow

forms as previously constructed have made no provision for holding the strap or straps in extended position. The present invention provides for holding the strap or straps in the desired position and contemplates the provision of strap holding means adapted to be set and secured at any desired position or angle relative to the form proper.

As the heel portion of such thin walled forms is subjected to the hardest usage, the present invention contemplates reinforcing the form at this point, the means employed being such as readily to permit the heel portion to be made stiff, non-collapsible and substantially unyielding if desired.

In the accompanying drawings,

Fig. 1 is a side elevation of a completed form showing it just at the completion of the process of making it;

Fig. 2 is a bottom view of the same form;

Fig. 3 is a top view of the form of Fig. 1;

Fig. 4 is an edge elevation of a bridge member or support adapted to be applied to the improved form;

Fig. 5 is a fragmentary plan view to large scale of the toe portion of a blank useful in making the form; and

Fig. 6 is a side elevation of a form similar to Fig. 1 but provided with a plurality of strap supporting bridge members.

Referring to the drawings the numeral 1 indicates a blank of sheet material suitable for making the improved form F. This blank is preferably transparent and preferably of celluloid or some material having generally similar characteristics. For certain uses it may be desirable to employ colored transparent material and in such case I prefer to color the blank just prior to moulding or to color the forms after moulding.

Preferably the toe portion 1^a of this blank is provided with a series of notches 2 (Fig. 5). Blanks of this character may readily be cut from sheet material by means of a suitable die and after softening in any suitable manner the blank is moulded by drawing it around a last of substantially the same size and contour as that upon which the shoe was made with which the form is to be used. In my Patent No. 1,585,284 dated May 18, 1926,

I have disclosed a process and apparatus useful in moulding blanks of sheet celluloid or similar material to produce shoe forms of the general type to which the present invention relates, and reference may be had to said patent for further details of one desirable process of moulding such forms.

In moulding the form it is preferred to turn in the lower edge of the blank to provide an inwardly directed bottom flange 3. By providing the notches 2 at the toe portion of the blank the flange 3 may be kept smooth and devoid of plaits or wrinkles at the toe portion. This is very desirable not only from the standpoint of improved appearance, but also since it provides a smooth surface facilitating the insertion in or withdrawal of the form from the shoe and also avoids any increase in height of the toe portion of the form such as is occasioned when wrinkles are produced at the forward end of the flange.

The rear ends 5 and 6 of the blank are caused to overlap as indicated in Figs. 2 and 3 so that the heel portion of the form consists of two plies, thus reinforcing and strengthening this part of the form. Ordinarily, these overlapping plies are left unconnected but if the user wishes a form having an unyielding heel portion, the overlapping plies 5 and 6 may be permanently united by moistening their opposed faces with a suitable solvent of celluloid, for example, acetone, and subjecting them to pressure sufficient to cause the opposed surfaces to adhere integrally. Obviously other modes of securing these parts, for example rivets, might be employed.

As disclosed in my patent above referred to I prefer to unite the opposite sides of the form at the ball portion by means of a connecting member 7, whose opposite ends 8 and 9 are secured to the flange 3. Preferably, as disclosed in the aforesaid patent, this connecting member 7 is of two-ply construction and the plies are separated at opposite ends and straddles over the edges of the flange 3, being united thereto in an integral manner by moistening their opposed surfaces with a celluloid solvent and keeping them in contact until they are integrally united. Preferably the cone portion 11 of the form, as herein disclosed, is imperforate so as to provide a very rigid support for the vamp portion of the shoe upper.

During the process of making sheet celluloid its original rough surface is treated to make it smooth and glossy but in moulding the hollow forms of the present invention this gloss to some extent disappears leaving the surface dull and striated. After the form has been substantially completed I restore the smooth and glossy surface by dipping the form in a solution, preferably consisting of from four to five parts of acetone to one part of alcohol. If it be desired to color the form

I prefer to add the dye to this smoothing solution. This has the effect of applying a thin coat of colored celluloid to both the inner and outer surfaces of the form. Obviously colored sheet celluloid could be employed if desired but I prefer to color the completed form as just described since the exact shade desired may be readily attained in this manner.

Sometimes, especially on damp days the forms become cloudy or veiled when drying from the smoothing operation and the desired gloss and transparency can be restored by immersing the form in a cleaning bath consisting of the vapor of a celluloid solvent, for example ethyl acetate.

After the form has been completed to the point thus far disclosed, it is preferably inserted in the shoe with which it is to be used, the upper edge 10^a of the form as originally made extending up above the upper edge of the shoe upper. The outline of the edge of the shoe upper is now marked upon the surface of the form in any suitable manner, as for example, by means of a knife point, pencil or other marking implement and the form is now removed from the shoe and the projecting edge of the form is trimmed down to the marked line, leaving the upper edge of the form as indicated at 10 in Fig. 1. This trimming may be accomplished by means of suitable shears, a sharp knife or a lining trimming machine, it being obvious of course that other trimming means such for example as disclosed in my application for patent Serial No. 129,769, filed August 17, 1926 may be employed and that if suitable trimming means be selected the trimming may be done without removing the form from the shoe. After trimming, the edge of the form may be buffed, either by the use of sandpaper held in the hand of the operator, or by means of a suitable buffing machine such as is commonly used in shoe factories for smoothing the bottom of the outer sole of a shoe. After trimming, and whether or not the edge has been buffed, the edge may if necessary be finished by rubbing it with a celluloid solvent, for example, acetone, which leaves a smoothly rounded polished edge.

The form is now reinserted in the shoe, if it was removed for trimming, and if the shoe be a strap pump, an arched or U-shaped bridge piece or strap support 12 is positioned in such a manner as to form a support for holding the strap in the normal position of use with its free end buttoned or otherwise attached to the shoe.

This bridge or strap support 12 is preferably of two-ply construction, consisting of two pieces 13 and 14 of sheet material preferably like that used for making the form proper, these pieces 13 and 14 being united except adjacent to their ends. Preferably this bridge piece 12 is shaped to conform substantially

to the edge contour of the strap which it is intended to support, that is to say, if the strap has substantially parallel edges as here shown, the bridge piece will also have parallel edges and be of substantially the same width; on the other hand, if the strap have ornamental or irregular edges the bridge piece 12 may, if desired, be shaped to correspond.

10 The members 13 and 14 forming the bridge piece are suitably bent or arched so as to hold the strap extended in the position in which it would be held by the instep portion of the wearer's foot. Since the end portions 15 of the members 13 and 14 forming the bridge piece are not united, they may be separated as shown in Fig. 4 to provide the spaces 15 and 16 respectively, which are adapted to receive the upper edge portions of the opposite 20 walls of the form. The ends of the bridge piece having been straddled over the edges of the form, the bridge piece is moved back and forth, from front to back of the form and angularly, until it assumes the proper position 25 to support the strap in the position of use. The surfaces of the members 13 and 14 which engage the walls of the form are moistened with a suitable solvent or cement and the bridge piece is now temporarily clamped 30 in position in any suitable manner until the solvent or cement has set, thus permanently uniting the bridge piece to the form proper.

Since some pumps have a plurality of straps, several such bridge pieces may be 35 provided. Such an arrangement is shown in Fig. 6 where the form F is shown as provided with two bridge pieces 12 and 12^a respectively.

I claim:

40 1. That process of preparing shoe forms which comprises as steps moulding celluloid to conform substantially to the interior of the shoe with which the form is to be used, trimming the upper edge of the moulded 45 form substantially to correspond to the edge of the shoe upper and smoothing the trimmed edge by the use of a celluloid solvent.

2. That process of making shoe forms which comprises softening a blank of transparent celluloid, moulding the softened blank to conform substantially to the interior of the shoe with which it is to be used, permitting the moulded form to regain its stiffness, inserting it in the shoe, trimming the form to 55 correspond to the contour of the edge of the shoe, and smoothing the trimmed edge of the form by the use of a celluloid solvent.

3. That process of making shoe forms which comprises preparing a blank of sheet celluloid, softening the blank, moulding the softened blank to conform to the inside of a shoe upper, permitting the form to regain its stiffness, trimming the upper edge of the moulded form to correspond to the contour 65 of the upper edge of the shoe in which it is

to be placed, smoothing and softening the trimmed edge by the use of a celluloid solvent, and attaching a bridge member to the upper part of the form.

4. That process of preparing shoe forms which comprises as steps, moulding a celluloid blank into a form having toe and heel portions and conforming substantially to the interior of the shoe with which the form is to be used, overlapping ends of the blank to 70 form the heel portion, trimming the upper edge of the form to correspond substantially with the edge of the shoe upper and smoothing the trimmed edge by the use of a celluloid solvent.

5. That process of preparing shoe forms which comprises as steps, moulding a celluloid blank into a form having toe and heel portions and conforming substantially to the interior of the shoe with which the form is to be used, overlapping ends of the blank to 75 form the heel portion, inserting the form into the shoe, trimming the edge of the form to correspond substantially with the edge of the shoe upper and smoothing the trimmed edge by the use of a celluloid solvent.

Signed by me at Auburn, N. Y., this 23rd day of May, 1927.
